UNITED STATES PATENT OFFICE.

HENRY J. HICKEY AND WARNER E. McMULLAN, OF FORT DODGE, IOWA.

DESIGN FOR A STREET-DIRECTION AND ADVERTISING DEVICE.

56,157.

Specification for Design. Patented Aug. 24, 1920.

Application filed June 19, 1919. Serial No. 305,443. Term of patent 3½ years.

To all whom it may concern:

Be it known that we, HENRY J. HICKEY and WARNER E. McMULLAN, citizens of the United States of America, and residents of Fort Dodge, Webster county, Iowa, have invented a new, original, and ornamental Design for a Street-Direction and Advertising Device, of which the following is a specification.

Our invention consists in the new, original and ornamental design for a street di-

rection and advertising device as herein claimed and illustrated by the accompanying drawing, in which—

Figure 1 is a plan and Fig. 2 is an elevation of a street director and advertising device embodying our design.

We claim as our invention—

The ornamental design for a street direction and advertising device as shown.

HENRY J. HICKEY.
WARNER E. McMULLAN.
